(74) Attorney, Agent, or Firm—Brouse McDowell; Heather M. Barnes

(57) **CLAIM**

The ornamental design for a reversible foot pedal, as shown and described.

DESCRIPTION

FIG. 1 is a perspective view of the present invention.

FIG. 2 is a top plan view of FIG. 1.

FIG. 3 is a left side view of FIG. 1.

FIG. 4 is a front elevational view of FIG. 1.

FIG. 5 is a right side view of FIG. 1; and,

FIG. 6 is a bottom view of FIG. 1.

The broken line showings of the strap, treads and spindle are included for the purpose of illustrating environmental structure and form no part of the claimed design.
